Primary Examiner — Kathleen L Jones*Assistant Examiner* — Jasmine L. Comedy(74) *Attorney, Agent, or Firm* — Heslin Rothenberg Farley & Mesiti P.C.(57) **CLAIM**

The ornamental design for a lighting fixture with refractors, as shown and described.

DESCRIPTION

FIG. 1 is a front right perspective view from above of a lighting fixture with refractors according to the new design; FIG. 2 is a front left perspective view from below thereof; FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The broken lines in the drawings illustrate portions of the environment that form no part of the claimed design.

1 Claim, 5 Drawing Sheets(56)
